US0D1083156S

(12) **United States Design Patent** (10) **Patent No.:** **US D1,083,156 S**
(45) **Date of Patent:** **** Jul. 8, 2025**

(54) **BEAUTY LAMP**

(71) Applicant: **Shenzhen Ulike Smart Electronics Co., Ltd.**, Shenzhen (CN)

(72) Inventor: **Yuan Yang**, Shenzhen (CN)

(73) Assignee: **Shenzhen Ulike Smart Electronics Co., Ltd.**, Shenzhen (CN)

(**) Term: **15 Years**

(21) Appl. No.: **29/954,899**

(22) Filed: **Jul. 30, 2024**

(30) **Foreign Application Priority Data**

Mar. 13, 2024 (CN) 202430128025.4

(51) LOC (15) Cl. **24-01**

(52) U.S. Cl.

USPC **D24/209**

(58) **Field of Classification Search**

USPC D24/209, 210, 158, 200, 231, 185;
D26/39, 51, 120

CPC A61N 2005/0652; A61N 2005/0659; A61N

(57) **CLAIM**

The ornamental design for a beauty lamp, as shown and described.

DESCRIPTION

FIG. 1 is a front perspective view of a beauty lamp, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a left side perspective view of its folded state thereof;

FIG. 10 is a right side perspective view of its folded state thereof;

FIG. 11 is another left side perspective view of its folded state thereof;

FIG. 12 is a right side perspective view of its folded state showing the panel opened;

FIG. 13 is a rear perspective view of its expanded state thereof; and,

FIG. 14 is a front perspective view of its expanded state.

1 Claim, 14 Drawing Sheets
